Specification of Letters Patent.

Patented Nov. 9, 1915.

Application filed July 13, 1915. Serial No. 39,586.

To all whom it may concern:

Be it known that I, FREDERIC P. GATES, a citizen of the United States of America, and residing at Hartford, in the county of Hartford and State of Connecticut, have invented a certain new and useful Improvement in Keys, of which the following is a specification.

My invention relates to keys and particularly to a key for operating a screw plug or the like, the object of my invention being to provide a device of this character having certain features of novelty hereinafter pointed out and shown in the accompanying 15 drawing in which—

Figure 1 is a side elevation partially in section of a key in which my invention is embodied in one form; and Figs. 2 and 3 are partial views of one end of the key showing 20 the same in different positions.

In keys for operating screw plugs or the like it has commonly been the practice to provide the same with a squared end engaging the end of a plug and passing through 25 the nipple into which the plug is threaded. As a consequence of this construction it has frequently resulted in the accidental rotation of the plug to such an extent that it escapes the nipple, thus being placed in 30 operative position and requiring a readjustment in its nipple. The construction which I have now devised for the key prevents such accidental displacement of the plug by limiting the extent to which the portion 35 of the key in operative engagement with the plug can be inserted during the rotation of the key in a direction to advance the plug inward through the nipple, while at the same time permitting such portion of the 40 key to reengage the plug when it is desired to rotate the latter in the reverse or outward direction in its nipple.

As here shown the key comprises a shell or casing 10 rigid with the thumb piece 11 and provided with a cam slot 12. Within 45 this casing 10 I arrange the socket stud 13 having a pin 14 which enters the cam slot 12 of the casing. The screw plug 15, working in the threaded nipple 16 is provided 50 with a squared end 17 adapted to enter the engaging well 18 in the socket stud 13 of the key. The diameter of the stud portion of the key is such that it freely enters the bore of the nipple 16 while the diameter of the 55 cylindrical casing 10 is substantially the

same as that of the nipple itself, so that the end of the casing 10 forms an abutment limiting the inward travel of the socket 60 13 on the rotation of the key in a direction to force the screw plug inward through the nipple 16. The cam slot 12 is of such shape that on the rotation of the key in a direction to force the plug inward, the pin 14 on the stud travels to that end of the slot 12 which is most distant from the end of the 65 casing 10. The stud 13 is thus drawn into the latter to its greatest extent and projects beyond the end of the casing only the predetermined distance to which it is desired to limit the extent of inward travel of the plug 70 15. Obviously upon continued rotation of the key after the end of the casing 10 bears against the outer end of the nipple 16, has the effect of screwing the plug farther through the nipple but simultaneously with- 75 drawing its squared end 17 from the socket well 18, in the end of the stud 13, until, as shown in Fig. 2, it is completely withdrawn and the engagement between the same broken. Upon reverse rotation of the key 80 the pin 14, on the stud 13, travels through the cam slot 12 to the end of the latter adjacent the end of the casing 10 thus further extruding the stud from the casing and permitting the stud to enter farther into the 85 nipple 16 and thus again engage the squared end 17 of the plug 15. Since the pin 14 bears against the end of the slot 12, the reverse rotation of the key has the effect of unscrewing the plug and drawing it out from 90 its inserted position.

It is obvious that by the construction shown it becomes impossible to screw the plug 15 inwardly beyond the predetermined distance at which its engagement with the 95 socket of the operating key is broken. Nevertheless the same key may be employed to withdraw the plug by reason of the extension of the stud on the reverse rotation of the key.

Various modifications of the construction will readily suggest themselves to those skilled in the art without departing from what I claim as my invention.

I claim as my invention:—

1. As a new article of manufacture, a key comprising an abutment member and a screw engaging member, and a cam connection between the same serving to extrude the screw engaging member on clockwise 110

rotation of the key and retract the same on contra-clockwise rotation of the key, for the purpose described.

2. As a new article of manufacture, a key comprising a casing and a screw engaging stud member within the same, and a cam connection between said stud and casing serving to extrude the stud on clockwise rotation of the key and retract the same on contra-clockwise rotation of the key.

3. As a new article of manufacture, a key comprising a casing and a screw engaging stud member within the same, a cam slot in

said casing and a pin on the stud entering said cam slot and serving to extrude the 15 plig on the clockwise rotation of the key and retract the same on the contra-clockwise rotation of the key.

In testimony whereof I have signed my name to this specification, in the presence 20 of two subscribing witnesses.

FREDERIC P. GATES.
